(57) **CLAIM**

The ornamental design for an adjustable measuring spoon, as shown and described.

DESCRIPTION

FIG. 1 is a perspective view of the adjustable measuring spoon;

FIG. 2 is a side elevation view of the adjustable measuring spoon;

FIG. 3 is a top plan view of the adjustable measuring spoon;

FIG. 4 is a front elevation view of the adjustable measuring spoon;

FIG. 5 is a bottom plan view of the adjustable measuring spoon;

FIG. 6 is a perspective view of a smaller version of the adjustable measuring spoon shown in FIGS. 1 through 5;

FIG. 7 is a side elevation view of the adjustable measuring spoon shown in FIG. 6;

FIG. 8 is a top plan view of the adjustable measuring spoon of FIG. 6;

FIG. 9 is a front elevation view of the adjustable measuring spoon of FIG. 6;

FIG. 10 is a bottom plan view of the adjustable measuring spoon of FIG. 6;

FIG. 11 is a perspective view of an alternate embodiment of the adjustable measuring spoon shown in FIGS. 1-10;

FIG. 12 is a side elevation view of the adjustable measuring spoon of FIG. 11;

FIG. 13 is a top plan view of the adjustable measuring spoon of FIG. 11;

FIG. 14 is a front elevation view of the adjustable measuring spoon of FIG. 11; and,

FIG. 15 is a bottom plan view of the adjustable measuring spoon of FIG. 11.
